[57] CLAIM

The ornamental design for a physical exerciser, as shown and described.

DESCRIPTION

FIG. 1 is a right side elevational view of a physical exerciser showing my new design, the side opposite being a mirror image;

FIG. 2 is a rear elevational view thereof;

FIG. 3 is a front elevational view thereof;

FIG. 4 is a top plan view thereof;

FIG. 5 is a cross-sectional view thereof taken along line 5—5 in FIG. 4; and,

FIG. 6 is a bottom plan view thereof.
